UNITED STATES PATENT OFFICE.

MILTON S. KUHNS, OF KUTZTOWN, PENNSYLVANIA.

NECKTIE-STRETCHER.

1,302,383.

Specification of Letters Patent. Patented Apr. 29, 1919.

Application filed February 8, 1918. Serial No. 216,079.

To all whom it may concern:

Be it known that I, MILTON S. KUHNS, a citizen of the United States, residing at Kutztown, in the county of Berks and State of Pennsylvania, have invented new and useful Improvements in Necktie-Stretchers, of which the following is a specification.

This invention comprehends the provision of a device adapted to be positioned within 10 a necktie or the like when the latter is not in use, for the purpose of stretching and pressing the tie.

The device consists of a pair of members pivotally connected at one end so as to be 15 separated or spread subsequent to being positioned within the tie, coöperating means being carried by the opposite extremities of the device for holding the members in active position.

20 The chief characteristic of the present invention resides in the provision of a peculiarly constructed flat element carried adjacent the free extremity of one of said members and desiring to coöperate with 25 means carried by the other member for effectively holding the members in extended in active position, as well as closely associated in a collapsed condition.

The nature and advantages of the invention 30 will be better understood when the following detailed description is read in connection with the accompanying drawings, the invention residing in the construction, combination and arrangement of parts as 35 claimed.

In the drawings forming part of this specification like numerals of reference indicate similar parts in the several views and wherein:—

40 Figure 1 is a view of the device within a tie showing the manner of using the same.

Fig. 2 is a plan view of the device showing the active position of the members.

Fig. 3 is a similar view showing the device 45 in a collapsed or folded position.

Fig. 4 is a sectional view taken on the line 4—4 of Fig. 3.

The device forming the subject matter of my invention embodies a pair of elongated 50 members 10 and 11 respectively which may be constructed from any suitable material, length and configuration. The members are pivoted together at one end in any suitable manner, the link 12 being utilized for this 55 purpose in and pivoted to each of said members. As herein above stated, the device is

primarily designed for use for stretching neckwear or like and as shown in Fig. 1 is adapted to be positioned within the tie in a manner whereby the members 10 and 11 60 lie in adjusted positions to the opposite longitudinal edges of the tie. By reason of the pivotal connection between said members, the latter can be spread or separated the required distance to effect stretching of the 65 tie, so that when the device is removed the tie will assume a tidy and substantially flat condition.

With a view of holding the members 10 and 11 respectively fixed relatively in extended or folded positions, use is made of a locking element 13 pivoted as at 14 upon the members 10 adjacent the free extremity thereof. A plurality of equidistantly spaced pins or teeth 15 project from one of the longitudinal edges of the locking element and are adapted to engage a stud 16 carried by the member 11 to hold said members fixed relatively in active position. When the locking element is used in this capacity it is 80 disposed transversely of the device bridging the space between the members and can vary in length to permit of any desired adjustment of the members 10 and 11. The stud 16 is disposed substantially in alinement 85 with the pivot 14 so that the members 10 and 11 are closely associated in a collapsed condition as clearly shown in 3, the hook like extremity 17 of the locking element is capable of assuming a position to engage the stud 90 16, thus effectively retaining the members 10 and 11 fixed relatively in folded positions. The hook like extremity 17 is caused to assume position for this purpose by swinging the latch element upon its pivot to lie parallel with and upon the members 10. This arrangement obviously provides for compactness, so that the device in its entirety occupies a minimum of space when not in use. The hook-like extremity 17 of the latch 10 member is preferably although not necessarily formed with a cam surface 18 to maintain its engagement with the stud 16 in the manner illustrated in Fig. 3. Again the stud 16 is so spaced with respect to the pivot 14 of the latch and in transverse alinement therewith, that when the members 10 and 11 are brought together in a folded position, it necessitates the hook-like extremity being forced into engagement with the stud 16, thus holding the members 10 and 11 together under tension.

- While it is believed that from the foregoing description the nature and advantages of the invention will be readily apparent, I desire to have it understood that
- 5 what is herein shown and described is merely illustrative of the preferred embodiment of the invention, to which I do not limit myself, and that such changes may be resorted to when desired as fall within the scope of
- 10 what is claimed.
- What I claim:
1. A device of the class described comprising a pair of pivotally connected members, a stud carried by one of said members, a
- 15 latch element pivoted upon the other member, pins projecting from said element to engage said stud with the element disposed transversely of said members, whereby the latter are held fixed relatively in extended
- 20 positions, said element having a hook like extremity adapted to be brought into en-

gagement with said stud when said element is disposed parallel with said members, thus holding said members fixed relatively in a folded position.

2. A device of the class described comprising a pair of members pivotally connected together at one end, a stud projecting from one of said members, a latch element pivotally mounted upon the other of said members, and designed to engage the stud to hold said members fixed relatively, when the latch element is arranged to bridge the space between the members, and said element being further designed so that when the element

25

30

35

is in a position parallel with one of the members it engages the stud to hold said members fixed relatively in contacting engagement.

In testimony whereof I affix my signature. 40

MILTON S. KUHNS.
